UNITED STATES PATENT OFFICE

ROSS F. GEORGE, OF SEATTLE, WASHINGTON

UNDER AND OVERFEEDER FOR PENS

Application filed November 18, 1929. Serial No. 407,975.

My invention relates to an improvement in pens and fountain attachments therefor. The conception of fountain attachments for pens, whether of the underfeeder or overfeeder type or the two combined, is not a new one. Such feeders have been employed heretofore, and have been made in various forms. The chief drawback to more extended use thereof, however, has been the difficulty of cleaning them. It is the chief object of my invention, then, to produce such feeders, especially an overfeeder, or an overfeeder combined with an underfeeder, which are easily cleaned, and which, in the combined form, may be so connected that when one is opened up for cleaning the other feeder is simultaneously released or opened, and when one is closed the other is closed thereby, or to provide that movement of one feeder, towards open or towards closed position, moves the other feeder similarly.

Another object is the provision of such closing and holding means which is frictional in character, and therefore easily released or engaged, yet amply firm in use.

Another object is the provision of feeders of this type which are simply constructed, and which may be simply connected to the pen, or mounted thereon.

Especially is it an object to provide such feeders which may be cheaply manufactured and assembled, and which can be assembled, in some instances, by merely snapping into place on the pen.

My invention comprises the novel parts, and the novel combination and arrangement thereof, as shown in the accompanying drawings, described in the specification, and more particularly defined by the claims terminating the same.

In the accompanying drawings I have shown my invention embodied in various forms of feeders, and secured to the pen in various ways.

Figure 1 is a side elevation, and Figure 2 a longitudinal section of one form of connection between the underfeeder and overfeeder, wherein is provided a means for positively moving the two feeders together, both in opening and in closing.

Figure 3 is a transverse section through this type of feeder, on the line 3—3 of Figure 1.

Figure 4 is a longitudinal section similar to Figure 2, and Figure 5 a transverse section on line 5—5 of Figure 4, showing a modified form of combined feeder.

Figure 6 is a longitudinal section through a simplified form of combined feeder, differing from the forms shown in Figures 1, 2, 55 and 3 largely in that the positive operative connection between the two feeders operates only in closing, and opening the one feeder does not necessarily open the other.

Figure 6a is an enlarged detail of the hinge 65 of the overfeeder in Figures 1, 2, 3, and 6.

Figure 7 is a longitudinal section, and Figure 8 a transverse section on the line 8—8 of Figure 7, showing a further modification, which provides positive connection at all 70 times between the two feeders, and a modified pivot means therefor.

Figure 9 is an enlarged view of this pivot means shown in the open position.

Figure 10 is a longitudinal section, and Figure 11 a cross section on the line 11—11 of Figure 10, showing a further modified construction, particularly a modified hinge arrangement, and Figure 12 is a bottom plan view of the same.

Figure 13 is a longitudinal section through a pen and combined feeder, showing a further modified hinge arrangement.

Figure 14 is a longitudinal section through a hinge arrangement modified to adapt it to 85 an overfeeder alone, and Figure 15 a like view of a modified hinge arrangement adapted to an underfeeder, Figure 16 being a perspective view of the latter.

Figure 17 is a longitudinal section through 90 a combined overfeeder and underfeeder, the one feeder being supported from the other, rather than directly from the pen itself.

Figure 18 is a longitudinal section through 95 a form of underfeeder and overfeeder associated with the pen, in which the two feeders are associated only in that the one opens the other, and Figure 19 is a transverse section therethrough on the line 19—19 of Figure 18.

Figure 20 is a longitudinal section through 100

a pen and under and overfeeders associated therewith, in which each of the feeders is independently movable into open or closed position, and Figure 21 is a transverse section on line 21-21 of Figure 20.

Figure 22 is a longitudinal section through a pen and overfeeder, in which the feeders are not only independent of one another, but in which only the underfeeder is movable 10 away from the pen for cleaning, and Figure 23 is a transverse section on the line 23-23 thereof.

Figure 24 is a longitudinal section through a modified form, in which the underfeeder 15 and overfeeder are independent, except as the one is moved to open position by movement of the other, and Figure 25 is a transverse section on the line 25-25 of Figure 24. Figure 26 is a perspective view illustrating 20 a manner of holding an ink feeder to the pen.

Perhaps the simplest form of the invention is shown in Figure 6. In this view the shank of the pen 1 is transversely slotted, as indicated at 11, and the overfeeder 2 is provided with a heel 21, which projects through this slot 11. In this manner, a hinge connection is formed, and, if desired, some means may be provided for preventing the loss of the overfeeder by dropping from the slot 11. The underfeeder 3 is hinged in some suitable manner to the body 13 of the pen, as by trunnions 32 (see Figure 3) received in small holes 14 of the two sides of the pen body. This underfeeder 3 is provided with a heel 31, which is bent toward the heel 21 of the overfeeder, and the parts are so proportioned and arranged that when in closed position with the tips of the under and overfeeders lying close to the tip 12 of the pen the heel 31 of the underfeeder will ride on the heel 21 of the overfeeder, and this heel may be made somewhat flexible or yielding, and in this manner the tips of the two feeders may be pressed flexibly against the tip of the pen, so as to provide proper capillary action, as is well understood. The frictional engagement of the heels 21 and 31 prevents accidental disengagement. To facilitate opening of the feeders one or both of them may be provided with an outwardly struck finger, as is indicated at 30 on the underfeeder, which may be engaged by the user's finger-nail to open the underfeeder. The overfeeder in this form will not necessarily open when the underfeeder is opened, through it will do so by gravity if held with the tip uppermost. However, closing of the underfeeder will necessarily close the overfeeder, since the heel 31 will engage and ride on the heel 21, causing the overfeeder to close.

In Figure 6a there is shown a means to prevent loss of the overfeeder 2, and this same means is illustrated in Figures 1, 2,

3, and 6. Essentially, this comprises a small hole or indentation 22 at the base of the overfeeder, and a small tip 15 struck up from the transverse slots 11 in the pen shank, which is either pressed backward into place in the 70 hole 22 of the feeder, or which may be left without striking it from the plane of the pen, and the feeder inserted by forcing its heel 21 past the flexible tip 15, which, when in registry with the hole or indentation 22, 75 will spring into place in this hole or indentation, and in that manner prevent loss or side play of the overfeeder.

In Figures 1 and 2 the underfeeder 3 is shown as provided with a toe 33, which engages with the upper side of the heel 21 of the overfeeder 2, just as the heel 31 engages with its under side. Thus, as the underfeeder is swung open, the toe 33 positively engages the heel 21 of the overfeeder, and causes it to swing open, and as or if the underfeeder is closed, engagement between the three members 33, 21, and 31 will positively cause the other feeder to close.

In Figures 4 and 5, it will be observed that 90 the heel 21 is provided with shoulders 23, the heel entering a slot 34 in the heel 31 of the underfeeder. By this arrangement the two feeders are somewhat loosely, yet positively, connected, so that they will necessarily act together, though, in this instance, the force tending to press the tips of the feeders to the tip of the pen is initiated from the overfeeder 2, rather than from the underfeeder 3, and hence the overfeeder has 100 the struck-up finger 20.

In this form, too, a modified hinge arrangement is shown, this consisting of ears 16 struck upwardly from the shank 10 of the pen, and having pivot recesses 16' pressed 105 therein, the overfeeder having correspondingly pressed ears 24, so that the overfeeder may be secured in place by the spring action of the ears 16 yielding sufficiently to permit the pivot bosses of the overfeeder to 110 snap into place in the recesses 16' of these ears 16.

In Figures 7, 8, and 9 the ideas expressed in Figures 4 and 5 are carried somewhat farther. The underfeeder 3 is provided with 115 ears 35 at its rear end, and the overfeeder 2 is provided with like ears 25, and a pin and slot connection, indicated at 4, may be the means positively connecting them to operate simultaneously. Similarly, the hinge arrangement is modified by causing the pivot recess 17 in the ears 16 to be somewhat elongated, and the slight pressed bosses 26 in the ears 25 to be correspondingly elongated, so 120 that when the two are in registry the tips of the feeders will be pressed by the spring action in these elongated pivot members, into close contact with the tip 12 of the pen, and yet will yield sufficiently to permit the 125

feeders to be opened, and to be held by friction in such open position.

Figures 10 and 11 illustrate a form of the feeders which is similar in many respects to the form of Figure 6, except that the small tip 15, as shown in Figures 3 and 6a, is omitted, and instead a tip 27 is struck from the base of the overfeeder 2, this tip 27 being forced through the transverse slot 11, and then engaging the under side of the pen. To prevent withdrawal of the heel 21, the underfeeder 3 may be provided with lateral projections 36, engaging the edges of the two sides of the pen body to position the feeder, and to be engaged by the two fingers of the user to open the feeders. This is best shown in Figure 12.

In Figure 13 a pivot arrangement similar to that described in connection with Figures 4 and 5 is employed, and in addition a member 28 is struck from the plane of the heel 21, this being somewhat flexible, and being engaged by the toe 31 to press the overfeeder 2 into closed position.

Figure 14 illustrates the invention insofar as it relates to the hinge means applied to an overfeeder alone, and the hinge connection is of the general type illustrated in Figure 10. However, as there is no flexible underfeeder, the heel of which may press against the heel of the overfeeder (as in Figure 10), it becomes necessary to provide means to secure the feeder in closed or operative position. Preferably this should be a frictional means, and consequently I show a tongue 19 which may be transversely grooved, struck downwardly from the shank 10 of the pen, and yieldable sufficiently to permit engagement of the heel 21 with its groove. This frictionally holds the feeder 2 in operative position.

Similarly, in Figures 15 and 16, the single underfeeder is frictionally held in closed position, the side edges of its heel 31 engaging in elongated recesses 18 in the pen body, these forming pivot recesses much after the fashion of those shown at 17 in Figures 8 and 9. Yielding of the pen sides themselves permits opening of the underfeeder 3 thus mounted.

In Figure 17 both feeders 2 and 3 are supported from the pen, but one directly and the other indirectly. Thus, the overfeeder 2 is pivoted on ears 24, as in the form of Figure 4, but the underfeeder 3 pivots in the heel 21 of the overfeeder, rather than in the pen 1. This pivot may be in the form of the elongated pivot recess, pressed in the side walls of the heel 21, as is shown in Figures 7, 8, 9, and 17, or of any other suitable form. As illustrated, movement of the overfeeder 2 into open position will force the friction lock between the heels 21 and 31, and the tips of the feeders 2 and 3 will separate, and may either or both be swung away from the pen for cleaning. To close, both are pressed to-

wards the pen until the friction lock between the two heels snaps into place.

In Figures 18 and 19 the feeders 2 and 3 are mounted each upon the pen 1 by a hinge connection, with the heel 21 of the overfeeder 70 2 turned back for engagement with a downwardly and forwardly inclined spring lug struck out from the pen material and indicated at 11'. This retains the heel 21 in position to hold the feeder 2 closed, and the heel 21 is immediately in the rear of the heel 31 of the underfeeder 3, which will engage therewith when the two feeders are open, to cause the overfeeder to move to closed position as the underfeeder is moved towards its 80 closed position or to cause the underfeeder to open as the overfeeder is opened. Otherwise, there is no cooperation between the two feeders, so far as their movement is concerned. 85

In Figures 20 and 21 the two feeders are wholly independent, so far as their movement is concerned. Each is provided with a pivotal connection to the pen 1, and each is movable independently of the other. 90

In Figures 22 and 23 the feeders are similarly independent of one another, but in this form the overfeeder 2 is provided with a tongue 21', which engages in a slot formed by oppositely struck cross pieces in the shank 95 95 of the pen, indicated in general at 10', whereby this tongue may be frictionally held in place to retain the overfeeder 2 upon the pen, but without the facility of movement with respect thereto except by detachment therefrom. The underfeeder, however, has its heel 31 frictionally engaged with a tongue 19 of the pen, whereby it may be thrown into open position or back into closed position. This form permits the underfeeder which is 100 difficult to get at unless it is pivotally connected to the pen, to be thrown back for cleaning, while the overfeeder, which is more accessible, can be cleaned through the open sides between its marginal edges and the pen. 105 110

In Figures 24 and 25 there is no positive connection between the two feeders, but the heel 21 of the overfeeder is positioned to be engaged by the heel 31 of the underfeeder to throw the overfeeder into closed position as 115 the underfeeder is moved towards closed position, and this heel 21 of the overfeeder is also engageable with a tongue 19' of the pen, thereby to more securely hold the overfeeder, and consequently the underfeeder, in closed position. There is thus provided a positive means of holding the two feeders in closed position, which means is independent of the means for moving one feeder from the other. 120

In Figure 26 another frictional means is 125 shown. In this form the pen 1 near the tip 12 is provided with upturned lugs 1' adapted to engage the side edges of the feeder 2, and thus hold it in position. It will be noted that the lugs, due to their particular shape, afford a 130

ruling edge for the pen. It will be seen that either over and under feeders, or both, may be held in this manner by providing both upturned and downturned lugs.

5. What I claim as my invention is:

1. In combination with a pen, an underfeeder and an overfeeder supported therefrom to lie close to the pen towards its tip, or to move away therefrom, and means controlling movement of one feeder from the other.

10. 2. In combination with a pen, an underfeeder and an overfeeder each pivotally supported on the pen to lie in operative position, close to the pen towards its tip, or to swing away from the pen, and means controlling movement of one feeder from the other.

15. 3. In combination with a pen, a pivotally mounted underfeeder and overfeeder supported therefrom, and movable from operative position, close to the pen towards its tip, to open position, spaced therefrom, and means connecting said feeders, said feeders,

20. their connecting means, and the pen being disposed and arranged to induce movement of one feeder from a selected position by movement of the other feeder from such position.

25. 4. In combination with a pen, an underfeeder and an overfeeder supported therefrom, each movable from closed position, near the pen, to open position, spaced therefrom, and means associated with said feeders to control movement of one feeder into closed position by movement of the other likewise into closed position.

30. 5. In combination with a pen, an underfeeder and an overfeeder supported thereon, each moveable from closed position, near the pen, to open position, spaced therefrom, and means carried by one feeder and engageable frictionally with the other feeder to move the latter into closed position as the former likewise moves into closed position.

35. 6. In combination with a pen, an underfeeder and an overfeeder supported thereon, each movable from closed position, near the pen, to open position, spaced therefrom, and means interengageable between the feeders to positively move one into closed position as the other is moved into closed position.

40. 7. In combination with a pen, an underfeeder and an overfeeder supported thereon, each movable from closed position, near the pen, to open position, spaced therefrom, and means interengageable between the feeders for positively moving one from one position to another as the other is correspondingly moved.

45. 8. In combination with a pen, an underfeeder and an overfeeder adapted to lie in operative position, close to the pen, pivot means supporting each of said feeders from the pen to swing from operative position to open position, for cleaning, and means inter-

engageable between the feeders permitting simultaneous movement thereof from one position to another.

9. In combination with a pen, having a shank transversely slit, an overfeeder having a heel passing through said slit, an underfeeder pivotally supported beneath the pen, and having a heel above the pivot, the heels of said overfeeder and underfeeder being of a size and so disposed that the underfeeder heel engages the overfeeder heel, as the underfeeder is moved into operative position, thereby to move the overfeeder into operative position.

10. In combination with a pen, having a shank transversely slit, an overfeeder having a heel passing through said slit, an underfeeder pivotally supported beneath the pen, and having a heel above the pivot, the heels of said overfeeder and underfeeder being of a size and so disposed that the heel of one frictionally engages the heel of the other, as one feeder moves into operative position, to thereby move the other feeder into operative position, the respective angles of the heels, in operative position, being such as to hold the feeders in such position.

11. In combination with a pen, having a shank transversely slit, an overfeeder having a heel passing through said slit, an underfeeder pivotally supported beneath the pen, and having a heel above the pivot, the heels of said overfeeder and underfeeder being of a size and so disposed that the underfeeder heel engages the overfeeder heel, as the underfeeder is moved into operative position, thereby to move the overfeeder into operative position, and means for preventing disengagement of the overfeeder from said slit.

12. In combination with a transversely slotted pen, a feeder attachment therefor having a heel projecting through the slot, and means on the pen located substantially at the slot, and yieldable to permit passage of the heel therethrough, said means providing interengagement between the feeder and pen to prevent withdrawal of the heel from the slot.

13. In combination with a transversely slotted pen, a feeder attachment therefor having a heel projecting through the slot and pivotally supported at the junction of the feeder and heel in this slot, and itself apertured at this junction, a tip formed in the pen and projecting into the feeder's slot, and yieldable to permit insertion of the heel through the slot, and engageable within the aperture in the feeder to prevent withdrawal of the feeder.

14. In combination with a pen having an underfeeder and an overfeeder mounted thereon and normally lying close to the pen towards its tip, and movable from such position away from the pen, and means interengageable between said feeders to move one positively from one position to the other, as

the second feeder is moved to corresponding position.

15. In combination with a pen, an underfeeder and an overfeeder supported therefrom to lie in operative position close to the pen towards its tip, or to move away therefrom, means controlling movement of one feeder from the other, and means tending to retain the feeders in operative position.
16. In combination with a pen, having a shank transversely slit, an overfeeder having a heel passing through said slit, said overfeeder being pivotally mounted at the point where the heel engages the slit, the heel of said overfeeder being perforated outwardly of the pivotal mounting, yielding means on the shank struck back from the slit away from the overfeeder, the yielding means passing through the perforation in the heel to prevent withdrawal of the overfeeder and to hold it in operative position, an underfeeder having a heel and pivotally mounted, both over and underfeeder being so disposed that the heel of one engages the heel of the other in such a manner that the first will close the second and the second will close the first.
17. In combination with a pen, an overfeeder and an underfeeder as in claim 16, the pivotal mounting of the underfeeder permitting it to swing from operative position to an open position without moving the overfeeder from operative position, the heel on said underfeeder lying in front of and engageable by the heel of the overfeeder when the latter moves to open position, thereby to open the underfeeder.
18. In combination with a pen and a feeder mounted thereon, flanges upturned from the edges of the pen, adjacent to its tip and embracing the tip of the feeder, to serve as a ruling edge for the pen.
19. In combination with a pen and a feeder mounted thereon, flanges upturned from the edges of the pen, adjacent to its tip, and embracing the tip of the feeder, to serve as a ruling edge for the pen, and lugs extending inwardly from the flanges, distant from the pen tip, to overlie and restrain the feeder against separation from the pen.
20. In combination with a pen and a feeder mounted thereon, a flange extending angularly from the edge of the pen, adjacent its tip, to serve as a ruling edge for the pen, and to prevent contact of the edge of the feeder with a guiding rule.

21. In combination with a pen and a feeder mounted thereon, flanges bent from the edges of the pen, adjacent its tip, to serve as a ruling edge for the pen, and lugs extending inwardly from the flanges, distant from the pen tip, to overlie and restrain the feeder against separation from the pen.

Signed at Seattle, Washington, this 13th day of November, 1929.

ROSS F. GEORGE.
